BY Victor J. Evans

ATTORNEY

UNITED STATES PATENT OFFICE.

FRED WILLIAM GOWLAND, OF PHILIPSBURG, PENNSYLVANIA, ASSIGNOR OF ONE-HALF TO FRANK COEN CROYLE, OF PHILIPSBURG, PENNSYLVANIA.

SPARK-PLUG-TESTING DEVICE.

Application filed November 7, 1925. Serial No. 67,628.

This invention relates to electrical testing apparatus and has for its object the provision of a novel device adapted to be engaged upon spark plugs and operable to short circuit a selected one or ones for the purpose of testing an engine for weak explosions, misfiring, knocks and other defects.

It is well known that it is a common practice among mechanics to short circuit a plug or plugs by means of a screw driver or the like which is simply brought into engagement with the central electrode of the plug and with a portion of the engine, the different plugs being shorted at different times in order to ascertain the conditions. This method is primitive and clumsy and frequently results in the loss of time besides not being accurate.

It is with the above facts in view that I have designed the present device which embodies movable elements engageable selectively with the central electrodes of spark plugs for short circuiting them, the arrangement being such that the operator's hands are left free, after setting the switches, so that he may do other things, it being moreover possible to short circuit a number of plugs at one time, which would obviously be impossible with the screw driver method.

Another object of the invention is to provide a device of this character which may be mounted permanently upon the engine so as to be ready for instant use whenever necessary or desirable.

Still another object is to provide a device of this character capable of being applied to plugs in pairs, adjustment being possible in accordance with the distance between the plugs.

An additional object is to provide a testing device of this character which will be simple and inexpensive in manufacture, easy to install and use, positive in action, efficient and durable in service, and a general improvement in the art.

With the above and other objects and advantages in view, the invention consists in the details of construction and arrangement of parts to be hereinafter more fully described and claimed, and illustrated in the accompanying drawing in which:

Figure 1 is a side elevation of the device

applied to a pair of spark plugs, one thereof being short circuited,

Figure 2 is a plan view of the device alone with both switch members in normal or inoperative position,

Figure 3 is a longitudinal section,

Figure 4 is a plan view of a modified form, and

Figure 5 is a longitudinal section through the modification.

Referring more particularly to the drawings the letter A designates a portion of the cylinder head of an engine and B represents a pair of spark plugs screwed thereto. In carrying out the invention I provide an elongated strip 10 of suitable insulating material slotted at both ends as shown at 11 so as to be engaged upon the central electrodes C of the spark plugs prior to the engagement of the binding nuts D thereon, these nuts consequently acting to clamp the strip in place. Located beneath and riveted or otherwise secured to the strip 10 is a metallic strip 12 formed with upstanding ears 13 passing through suitable slots 14 in the strip 10 and carrying pivoted metal arms 15 equipped with handles 16 of insulating material. Slidably mounted so through suitable holes at the center of the strips 10 and 12 is a plunger or stem 17 provided with heads 18 and 19 at its upper and lower ends, respectively, and encircled by a coil spring 20 which engages the plate 12 and the head 19 for holding the latter in contact with the cylinder head A. The pivoted arms 15 are shown in Figures 1 and 2 as vertically swingable so as to be capable of being brought into engagement with the binding nuts D.

In the operation, it is apparent that by swinging any arm 15 into engagement with the adjacent spark plug, it may be short circuited. In actual testing it is of course apparent that when a plug is shorted and the engine does not slow down it is safe to assume that that particular plug is not functioning. It is also known that certain knocks are more readily detachable when the plug for that particular cylinder is not firing. In case of a multicylinder motor it is obvious that by shorting the various plugs at different times an efficient test may be

made to determine just what conditions exist. Clearly when the arms 15 are swung inwardly or toward each other as shown in Figure 2 they will have no effect whatsoever on the plugs and the device may consequently be left permanently in position ready for instant use.

In Figures 4 and 5 I have illustrated a slight modification in which I have disclosed 10 contact arms 21 pivoted at 22 and swingable horizontally to be brought into engagement with the central electrode or binding nut, as may be preferred, the arms 21 being preferably resilient so as to remain in engagement 15 with the plug if desired. This form operates in exactly the same manner as the other, the sole difference being the mounting of the contact arms.

From the foregoing description and a 20 study of the drawings it will be apparent that I have thus provided a simply constructed inexpensive and highly efficient device for the purpose specified which will satisfactorily perform all the functions for which it is 25 intended.

While I have shown and described a preferred embodiment of the invention it should be understood that I reserve the right to make such changes in the form, construction 30 and arrangement of parts as will not depart from the spirit of the invention or the scope of the subjoined claims.

Having thus described the invention I claim:

1. A device of the character described 35 comprising an elongated supporting member of insulating material slotted at its ends for engagement upon the central electrodes of adjacent spark plugs a metallic member secured to the underside of said insulating strip and having ears located above the strip, a spring pressed plunger slideable through both strips and in electrical contact with the metallic member and adapted to engage the engine to provide a ground connection and contact arms equipped with handles and pivotally mounted on said ears to be capable of swinging into engagement with the central electrodes of the spark plugs.

2. A spark plug tester comprising a metal 50 clip engageable upon the body of a spark plug an angular support of insulating material secured to said clip, an angular metallic member carried by said support and lying entirely thereagainst, said support and the 55 metallic member being apertured for engagement upon the central electrode of a spark plug, and a contact arm movably mounted upon said insulating strip in electrical connection with said clip and adapted to be engaged with said metallic member.

In testimony whereof I affix my signature.

FRED WILLIAM GOWLAND.
